UNITED STATES PATENT OFFICE

103,301

DESIGN FOR A SHOE

Pasquale Borda, Brooklyn, N. Y., assignor to Bancroft-Walker Company, Waltham, Mass., a corporation of Massachusetts

Application November 30, 1936, Serial No. 66,206

Term of patent 3½ years

To all whom it may concern:

Be it known that I, Pasquale Borda, a citizen of the United States, residing at 1448 85th Street, Brooklyn, in the county of Kings and State of New York, have invented a new, original, and ornamental Design for a Shoe, of which the following is a specification, reference being had to the accompanying drawing, forming a part thereof, in which the figure is a view in perspective of a shoe showing my new design, the heel being shown conventionally in dotted lines.

The dominant feature of my design resides in

a shoe having low cut open sides and a substantially plain tip vamp having a relatively long upwardly and rearwardly extending neck producing a high bootee effect, the vamp having spaced perforations of different sizes therethrough and a strap extending through the top end of the neck and anchored to the quarter.

I claim,

The ornamental design for a shoe substantially as shown and described.

PASQUALE BORDA.
